UNITED STATES PATENT OFFICE.

ADOLPH PETER GUSTAFSON, OF CHICAGO, ILLINOIS, ASSIGNOR TO M. SCHULZ CO., OF CHICAGO, ILLINOIS.

PNEUMATIC ACTION.

1,170,531.

Specification of Letters Patent.

Patented Feb. 8, 1916.

Application filed June 8, 1914. Serial No. 843,747.

To all whom it may concern:

Be it known that I, ADOLPH P. GUSTAFSON, a citizen of the United States, residing at Chicago, in the county of Cook and State 5 of Illinois, have invented a certain new and useful Improvement in Pneumatic Actions, of which the following is a full, clear, concise, and exact description, reference being had to the accompanying drawings, forming 10 a part of this specification.

My invention relates to pneumatic actions capable of being used in certain types of musical instruments, as for example player pianos and piano players, and also capable 15 of other uses.

Prominent objects of the invention are to provide an advantageous construction of pneumatic action; to simplify the same, reducing the number of parts and avoiding 20 complication in structure; to secure a high degree of accuracy and efficiency; to reduce the cost of construction and installation; to permit easy and ready access to the parts and dissassembling of the action for the purpose of repair and replacement; and to secure the foregoing and other desirable results in a simple and expeditious manner. 25

In the accompanying drawings Figure 1 is a view partly in elevation and partly in vertical section of a pneumatic action embodying my invention; Fig. 2 is a top plan of a portion of the same with certain parts broken away for convenience of illustration; and Fig. 3 is a bottom plan of a portion of 35 the same.

In the drawings I show a pneumatic action conveniently consisting of three members A—A, arranged one above the other, as shown in Fig. 1. Each of these parts or action members or chests supports a plurality or row of pneumatics B—B. The arrangement shown is intended for use in a player piano, the members A—A being sufficient to carry pneumatics B for all of the notes of 40 the piano which it is intended to operate and said members A being also of sufficient length to provide space for valve mechanisms for controlling said pneumatics. The pneumatics B are shown conveniently provided with projections C which are adapted to engage projections D on different vertically arranged rods or stickers E, whereby the piano action may be operated in the usual way by the pneumatic action. It will 45 be understood of course, that the pneumatic 50

action is capable of use for other purposes than in connection with a player piano or piano player.

Each action member or chest A is conveniently constructed of a board or member 1, 60 which extends longitudinally of and forms the principal part of said action chest A. This board or member 1 is provided at intervals along its top with apertures or recesses 2—2 forming valve chambers for 65 valves 3—3. The upper walls of valve chambers 2—2 are desirably formed by disk-like members 4—4 conveniently consisting of pasteboard disks having central apertures 5 which serve as air ports under the control 70 of the valves 3—3. Ducts or passages 6—6 extend from the valve chambers 2—2 downwardly to the lower surface of the board or member 1, opening into and communicating with apertures 7—7 in the tops of the pneumatics B whereby continuous passages are 75 formed from said valve chambers 2—2 to the interiors of the several pneumatics B—B. Preferably there are two such passages or ducts 6—6 from each valve chamber 80 2—2 as shown in Figs. 2 and 3, whereby a large and amply sufficient passageway to insure quick and instantaneous action is established between the several valve chambers and the interiors of the pneumatics. 85

A longitudinally extending groove or recess 9 is provided in the under surface of the board 1, such groove or recess forming a windway understood to be connected with the wind inducing apparatus, the under side 90 or wall of which windway is formed by cross boards 10—10. Apertures or ports 11—11 are formed between the valve chambers 2—2 and said windway 9, said apertures being preferably provided with metallic thimbles or sleeves 12—12 having upwardly extending angular beads 13—13 forming seats for the valves 3—3. 95

Small valve controlling or puppet pneumatics 14 are secured in position within the 100 windway 9. The swinging leaves of these pneumatics 14, that is the under leaves, are provided with rods 15 which have bent ends 16 extending up through the sleeves 12 and fitting into apertures in the under sides of 105 the valves 3—3. Passages or ducts 17 are formed in the board 1 communicating with apertures or openings 18 in the upper members of the pneumatics 14, said ducts or 110 passages 17 also communicating with small

chambers or recesses 19 formed in the upper surface of the board 1. Tracker tubes 20, understood to extend to a tracker board, are fitted to the board 1, as for example by being inserted in the side apertures or passages 21 communicating with the chambers 19. Small metallic cups 22 are set in openings formed between the chambers 19 and the windway 9, said cups 22 having small bleed ports 23. The chambers 19 are closed by small disks 24 secured to the upper surface of the board 1, which disks may conveniently be made of some suitable fabric, made or stamped in circular form and glued and shellacked to the upper surface of the board 1.

Thus it will be seen that normally the pneumatics B—B are in an expanded condition because of the communication of their interiors with the outside air through the ducts or passages 6—6 and ports 5—5. When, however, a perforation in the music sheet passes over the tracker board and air is admitted to a tracker tube 20, such air obtains access to the interior of the corresponding puppet pneumatic 14, thereby causing the expansion of said pneumatic, the result of which is that the valve 3 is lifted and closes its port 5 and opens the port 11 leading to the windway 9, whereupon the air is immediately exhausted from the pneumatic B by way of the passages 6—6 and the port or passage 11. Thus the pneumatic B is collapsed and the corresponding piano action is operated.

As a preferred arrangement the under surface of the board or member 1 and the boards 10—10 are inclined to the horizontal, as shown in Fig. 1, so that the angularity of the pneumatics B is compensated for, permitting the under side of said pneumatics to be horizontal or substantially so. The board 1 is preferably provided with projecting posts 27 supporting thumb screws 28 carrying abutments 29 adapted to coöperate with projections 30 on which are hinged ends of the pneumatics for permitting an adjustment of said pneumatics to the striking actions of the piano.

A layer of fabric 32 is preferably interposed between the pneumatics and the cross boards or strips 10—10 so as to serve to make an air tight joint between the strips 10—10, said strips being separated from one another by spaces 10^a—10^a, as shown in Fig. 3. The layer of fabric 32 closes said spaces 10^a—10^a, but may be removed in whole or in part to permit access to the pneumatics 14—14 by stripping off the whole or a portion of said fabric. In Fig. 3 a portion of the fabric is shown stripped off enough to open the two spaces 10^a—10^a shown in said figure and to permit access to the pneumatics 14 therein. When access is had to one or more of said valves by stripping off said fabric and

removing the corresponding pneumatics, the pneumatics and fabric may be again glued in place so as to make an air tight joint again.

It will be understood that changes and modifications may be made without departing from the spirit of the invention.

What I claim is:

1. A pneumatic action comprising a board or chest member having chambers formed in its upper portion, a windway formed in its lower portion, a pneumatic closing said windway, a valve controlling pneumatic, and a passage leading from each pneumatic to the windway. 80

2. A pneumatic action comprising a board or chest member having valve chambers formed in its upper portion, and having a windway formed in its lower portion and a pneumatic closing said windway. 85

3. A pneumatic action comprising a board or chest member having valve chambers formed in its upper portion, and having a windway formed in its lower portion, and also having ducts or passages from said valve chambers to the under surface of said board or member, a pneumatic closing said windway and connections between said pneumatic and said duct or passage. 90

4. A pneumatic action comprising a board or chest member having chambers formed in its upper portion, a windway formed in its lower portion, a pneumatic closing said windway, a valve provided in one of said chambers, a passage leading from said pneumatic to the valve chamber and thence to the windway, a passage leading from said windway to the other chamber, a port leading from said chamber to a valve controlling pneumatic, and connections from said pneumatic to the valve provided in said first mentioned chamber. 100

5. A pneumatic action chest having a member provided with a valve chamber in its upper portion, and a windway in its lower portion, and also having a port communicating with said valve chamber and windway, in combination with a valve controlling pneumatic secured within said windway and having a rod extending up through said port and a valve controlling said port and resting upon the upper end of said rod. 110

6. A pneumatic action comprising a board or member having its upper portion provided with chambers one of which is for a valve, said board also having ducts leading from said chambers to the under side of the board, the under side of said board being cut away to form a windway, cross boards separated from one another and secured to the lower side of said board or member, and valves in said valve chambers controlling the ducts or passages leading to the under side of the board, pneumatics arranged within said windway and secured to the por- 120

tion of the board or member forming the upper wall of the same, the under members of said pneumatics being movable, rods secured to said movable members of said pneumatics and having their ends bent upwardly and supporting said valves, ducts between the second mentioned chambers in the upper portion of said board or member, said ducts communicating with the interior of said pneumatics, metal thimbles having bleed ports interposed between said second mentioned chambers and said windway, disks having ports secured to the top of said board or member so as to form the upper walls and provide ports for said valve chambers, and other disks secured to the top of said windway and closing said second mentioned chambers.

7. A pneumatic action chest having its under side provided with cross strips or boards separated from one another to form intervening spaces, in combination with a layer of fabric extending along the under surface of said board or member and closing said spaces.

8. A pneumatic action chest having its under side provided with cross strips or boards separated from one another to form intervening spaces, in combination with a layer of fabric extending along the under

surface of said board or member and closing said spaces, and pneumatics secured to the under surface of said board and fabric.

9. A pneumatic action consisting of a board or member having valve chambers 35 and ducts or pasages, and also having a longitudinally extending groove or recess forming a windway, in combination with cross strips arranged crosswise of said board or member at the outer side of said windway, and a layer of thin material arranged outside of said cross strips.

10. A pneumatic action consisting of a board or member having valve chambers and ducts or passages, and also having a 45 longitudinally extending groove or recess forming a windway, in combination with cross strips arranged crosswise of said board or member at the outer side of said windway, and a layer of thin material arranged outside of said cross strips, and valve controlling pneumatics confined within said windway and located between said cross strips.

In witness whereof, I hereunto subscribe 55 my name this 3d day of June, A. D. 1914.

ADOLPH PETER GUSTAFSON.
